UNITED STATES PATENT OFFICE.

HARRY WEARNE, OF RIXHEIM, GERMANY.

DESIGN FOR WALL-PAPER.

SPECIFICATION forming part of Design No. 33,901, dated January 8, 1901.

Application filed December 18, 1900. Serial No. 40,313. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a section of wall-paper embodying the features of my design.

The leading features of the design consist in a circlet of stems, foliage, and flowers of the pink variety, including a bow ornament, and in the panel which extends from the top and bottom of the floral circlet, the panel being defined by bar-borders and ornamented between the borders by intertwining foliage sprays.

The minor features of the design consist in cruciform figures drawn within the floral cir-

clet and, further, in bars arranged in longitudinal series at each side of the floral circlet, forming side panels, the series of bars being interrupted at intervals by conventional floral figures, which also appear between the series of bars associated with dash figures. 25

Having thus described my invention, I claim as new and desire to secure by Letters Patent—

The design for wall-paper as herein shown and described.

In testimony whereof I have signed my name to this specification in the presence of two subscribing witnesses.

HARRY WEARNE. 30
